Jan. 15, 1963, Ser. No. 73,236

Term of patent 14 years

(Cl. D48—16)

FIGURE 1 is a bottom plan view of a lighting fixture diffuser showing my new design;

FIGURE 2 is one end elevational view thereof;

FIGURE 3 is an elevational view thereof as seen from the opposite end of FIGURE 2;

FIGURE 4 is a side elevational view thereof;

FIGURE 5 is a top plan view thereof with the decorative pattern partially shown for convenience of illustration;

FIGURE 6 is a cross-sectional view taken substantially in the plane indicated by line 6-6 of FIGURE 4;

FIGURE 7 is a bottom plan view of a modified form of lighting fixture diffuser;

FIGURE 8 is a side elevational view of the diffuser shown in FIGURE 7;

FIGURE 9 is a top plan view of the diffuser shown in FIGURE 7 with the decorative pattern partially shown for convenience of illustration;

FIGURE 10 is an end elevational view of the modified form of diffuser; and

FIGURE 11 is a cross-sectional view taken substantially in the plane indicated by line 11-11 of FIGURE 8.

The dominant features of my design reside in the solid line portions of the drawings.

This application is a continuation of my copending applications Serial Nos. D. 62,002 and D. 62,003 both filed on Sept. 2, 1960, and both now abandoned.

I claim:

The ornamental design for a lighting fixture diffuser, substantially as shown and described.
